[57] CLAIM

The ornamental design for a side plate for a level crossing between a road and a railroad, substantially as shown and described.

DESCRIPTION

FIG. 1 is a perspective view of a side plate for a level crossing between a road and a railroad, to be used outside the space between the two rails;

FIG. 2 is an end view of the side plate of FIG. 1;

FIG. 3 is a side elevation of the side plate of FIG. 1; as seen when looking at FIG. 1 from the top;

FIG. 4 is a top view of the side plate of FIG. 1;

FIG. 5 is a side elevation of the side plate of FIG. 1, as seen from the bottom of FIG. 1;

FIG. 6 is a bottom view of the side plate of FIG. 1.
